UNITED STATES PATENT OFFICE.

GEORGE H. HART, OF HARTFORD, CONNECTICUT.

ELECTRIC SWITCH.

1,297,348.

Specification of Letters Patent. Patented Mar. 18, 1919.

Application filed October 2, 1918. Serial No. 256,528.

To all whom it may concern:

Be it known that I, GEORGE H. HART, a citizen of the United States, residing at the city of Hartford, county of Hartford, State of Connecticut, have invented a certain new and useful Improvement in Electric Switches, of which the following is a full, clear, and exact description.

My invention relates to improvements in rotary snap electric switches and has for its object to produce a rotary snap switch in which the spindle for actuating the catch or bolt is relieved of driving strain. It further has for its object to produce a snap switch which is driven through the spring-hook or spring-plate with which one end of the spring directly engages, power being applied thereto independently of the spindle.

It further has for its object to produce a rotary snap switch in which the handle has a ratchet action, the spring-hook being so formed as to constitute one of the ratchet members.

It further has for its object in a marine switch, such switches comprising a switch mechanism contained within a water and gas-tight casing for use in connection with vapor-proof fittings and adapted for use upon vessels where it is desirable to protect the switch from moisture and in chemical and powder plants and the like, to provide a ratchet member carried by the cover and separable from the switch mechanism with the cover.

The following is a description of an embodiment of my invention, reference being had to the accompanying drawings, in which,

Figure 1 is a plan view of the inclosed marine switch;

Fig. 2 is a longitudinal section of the same;

Fig. 3 is a plan view of contact actuating mechanism;

Fig. 4 is a partial inner view of the inclosing casing;

Fig. 5 is a detail of the spring-plate or clip;

Fig. 6 is a detail of one of the ratchet members and its support;

Fig. 7 is a detail of the switch spindle;

Fig. 8 is a detail of the upper ratchet member shaft; and,

Fig. 9 is a holding plate for said shaft.

Referring more particularly to the draw-

ings, 1 is a casing having a cover 2 screwed thereon, the casing having tapped holes 3-3' for conduits for conductors leading to the switch mechanism. 4 is the switch mechanism which is of the ordinary step by step type having a stop-plate 5, a catch-plate 6, a catch-plate actuating member 7 for moving said catch-plate and carried by the spindle 8. Surrounding the spindle is the ordinary movable bushing 9 carrying the switch-plates 10 and propelled by the spring 11 whose lower end is engaged therewith, and whose upper end engages a spring-plate or hook 12, these parts, with the exception of the form of the spring-plate, being substantially as shown in Patent No. 753,881 dated March 8, 1904, and operating in the well known way.

The spring-plate has a key-hole slot 13 whose narrow portions slip into the slots 14 in the spindle, Fig. 7, and hold the plate from turning. The plate 12 is clamped in place by a nut 15. The plate 12 is formed with two projections 16 which extend above the general surface of the plate and constitute ratchet teeth.

Supported by the cover 2 is a co-acting ratchet member 17 having depending teeth 18 adapted to engage the teeth 16. This ratchet member 17 is carried by a sliding sleeve 19, which is held in downward position by the spring 20 and rotates with a shaft 21 by reason of splines 22 extending into slots in the sleeve. The shaft 21 extends through a packing box 23 having a compression nut 24, and is provided with a thumb-turn 25. The shaft 21 is held against vertical movement by a plate 26 secured to the cover and having a slot 27 whose sides enter an annular recess 28 in the shaft.

The switch above described is operated by turning the thumb-turn 25, which, through the shaft 21 and the ratchet clutch-member 17 supplies power direct to the spring-plate 12 and independently of the spindle for winding up the spring 9 and throwing the switch plates when the bolt has been moved to release the same. With this construction, the spindle 8 is relieved of the strain necessary for increasing the tension on the spring 9, and to which it is subjected in the construction of Patent No. 753,881, the function of the spindle in the present construction when turning in a forward direction being merely to carry the

catch-plate actuating element 7, which, on account of the connection of the spindle, is fixed relatively to the spring-plate. The spring-plate with its ratchet teeth and the ratchet member 12 act as a separable clutch to connect the shaft 21 with the spring 9 and spindle 8, this being a clutch connection such that the cover 2 carrying the shaft 21 can be removed and replaced with one 5 clutch member so as to separate and bring together the two clutch members. The shaft 21 of the clutch member 17, being removable with the cover 2, does not have to be removed from the stuffing box 23 when the 10 cover is removed and the plate 26 secured to the cover and engaging the groove 28 in the shaft holds it against axial movement in the 15 cover.

The switch mechanism is entirely inclosed 20 and, being operated by a ratchet mechanism carried by the cover, a reverse movement of the thumb-turn is possible without interfering with the switch mechanism. The thumb-turn 25 is provided with a recess 25 covering and inclosing the stuffing box 23 and compression nut 24 and protecting them.

As will be evident to those skilled in the art, my invention permits of various modifications without departing from the spirit 30 thereof or the scope of the appended claims.

What I claim is:

1. In a rotary snap switch having a stop-plate, a catch-plate, a spindle actuating said 35 catch-plate, a bushing revolving with said catch-plate and carrying the switch plates, the combination of a spring-plate rigidly secured to said spindle, a spring having one end directly engaging said spring-plate, and 40 switch-actuating means connected to said spring-plate independently of said spindle

for rotating said spindle through said spring-plate.

2. In a rotary snap switch having a stop-plate, a catch-plate, a spindle actuating said 45 catch-plate, a switch plate bushing carried by said spindle and rotating the said catch-plate, the combination of a spring-plate rigidly secured to said spindle, said spring-plate having ratchet teeth, a casing for said 50 mechanism, a cover therefor, a shaft carried by said cover, an axially movable ratchet member engaging said ratchet teeth and carried by said shaft, a spring interposed between said cover and said ratchet member 55 and holding said ratchet member normally in engagement with the teeth on said spring-plate, and a handle for turning said shaft, said ratchet member and said spring-plate constituting separable clutch members. 60

3. In a rotary snap switch, having a stop-plate, a catch plate, a spindle actuating said catch-plate, a switch plate bushing carried by said spindle and rotating the said catch-plate, the combination of a spring-plate rig- 65 idly secured to said spindle, said spring-plate having ratchet teeth, an axially mov-able ratchet member engaging said ratchet teeth, a shaft for supporting and rotating said ratchet member, a cover for said cas- 70 ing supporting said shaft, and a spring interposed between said cover and said ratchet member and holding said ratchet member normally in engagement with the teeth on said spring-plate, and a handle for turning 75 said shaft, said ratchet member being sep-able from said spring-plate, said cover having a stuffing box surrounding said shaft, and means for holding said shaft against axial movement within said stuffing 80 box.

GEORGE H. HART.
